UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

DISTRIBUTING APPARATUS.

1,311,915.

Specification of Letters Patent. Patented Aug. 5, 1919.

Application filed April 7, 1919. Serial No. 288,197.

To all whom it may concern:

Be it known that I, PAUL M. RAINY, a citizen of the United States, residing at Glen Ridge, in the county of Essex and 5 State of New Jersey, have invented certain new and useful Improvements in Distributing Apparatus, of which the following is a full, clear, concise, and exact description.

This invention relates to distributing apparatus and particularly to current impulse distributing apparatus of the rotary type. The main purpose of this invention is to provide an improved distributing mechanism suitable for printing telegraph systems 10 or the like, and one whereby current impulses may be distributed to the line or to suitable receiving apparatus in a reliable and efficient manner.

A further object is to provide a combined 20 structure which is neat and compact, one which may be readily regulated to operate at any desired speed, and which may be adjusted to compensate for variations in time required for various parts to operate. To 25 the above ends, there is provided a frame structure or housing on the opposite ends of which are mounted distributor faces, each comprising conducting rings which may be either continuous or segmented. The rings 30 of the distributor faces are adapted to be connected in pairs by means of commutator brushes carried by rotatable arms. The brush arms are, preferably, frictionally mounted on a continuously rotating shaft 35 and are adapted to be arrested and released once per revolution for synchronizing purposes. The rotary shaft carrying the brush arms may be rotated by any suitable driving mechanism, for example, a motor, and 40 the speed of the driving mechanism may be regulated while the distributors are in operation so that the distributors may be caused to travel in substantial synchronism and distribute the impulses at any desired rate 45 of speed.

The above and other objects of this invention will be fully set forth in the following description and claims, and will be more readily understood by reference to the accompanying drawings, wherein Figure 1 is a view in perspective of the distributing apparatus with a portion of the frame structure broken away to show part of the driving mechanism; Fig. 2 is a schematic cir-

cuit of the sending, distributing and receiving apparatus; Fig. 3 is an assembly view of the distributor and driving mechanisms; and Fig. 4 is a detail view of the electromagnetic release mechanism.

Referring particularly to Figs. 1 and 3, 55 the distributor frame structure or housing 10 is supported by upright members 11 and 12 on a base 13. On the base 13 is also mounted the distributor driving motor 14 and the motor speed control member 15. 60 The distributor shaft 16, carrying the distributor brush arms 17 and 18, is mounted at right angles to the motor driving shaft 19. The distributor shaft is, preferably, 65 positively driven by means of a gear wheel 20 carried thereby, coöperating with a spiral gear 21 on the motor driving shaft. While 70 a gear ratio of approximately 9 to 1 has been found suitable in actual practice, the ratio may obviously be varied to suit each 75 individual case and to provide the desired speed of the distributor brush arms. At the right hand of Fig. 3 is shown a couple of collector rings 22 and 23 and corresponding 80 conducting brushes 24 and 25. The collector rings and brushes are included in the circuit of the driving motor. In addition thereto is included a set of contacts (not shown) carried within a rotary casing 26, 85 which contacts are adapted to be opened by centrifugal force when the speed of the motor exceeds a predetermined R. P. M. The contacts are normally held closed by an adjustable spring member, and the tension of the spring member may be adjusted by turning 90 the knurled knob or disk 27 as fully disclosed in a co-pending application of Benjamin F. Merritt, Serial No. 194,146, filed October 1, 1917. The periphery of the knob or disk 27 extends through the sides of the 95 casing 26 and is adapted to be rotated in either direction while the motor is in operation. For this purpose, a flange 28 on one side of the casing 26 is adapted to be moved into the path of rotation of the disk 27, to 100 thereby turn it in one direction, and a flange 29 on the opposite side of the casing is adapted to be moved into the path of rotation of the disk 27 to thereby turn it in the opposite direction. The flange members 28 105 and 29 carried by the current control member 15 are pivotally mounted on the base 13 and may be moved into the path of the ro-

tary disk by moving a lever or operating handle 30 either to the left or to the right as desired, depending upon whether the tension of the spring member holding the contacts closed, is to be decreased or increased.

Rigidly secured to the housing 10 are two similar but irregularly shaped members 31, each of which supports a release magnet 32. Each member 31 is provided with a bifurcated extension 33 for guiding the reciprocatory movement of an arm 34 which is normally held by a spring member 35 in the path of its respective distributer brush arm. Each arm 34 is withdrawn from the path of the respective brush arm against the action of spring 35 whenever its magnet 32 is energized, as will presently appear. The bifurcated extension 33 is provided primarily to form a rigid support for the end of the arm 34, so that when the distributer brush arm strikes against the stop-arm 34, it will not cause vibration of the stop-arm and will not impose too great a strain on the stop-arm bearings.

The distributer faces are frictionally mounted within the housing 10 and they are arranged for orientation in order to insure distribution of the current impulses at the proper time intervals. For this purpose, an arm or lever 38 is provided for turning each distributer face, independently of the others, through any angle desired.

While in Figs. 1 and 3 only one distributer face is fully shown, it is to be understood that another distributer face is carried by the opposite end of the frame structure 10 and that, in fact, any number of distributer faces may be mounted in parallel planes, and corresponding distributer brushes carried by the rotary shaft 16 may be provided for traversing the several conducting rings of the distributer faces.

Referring now particularly to the schematic distributing circuit arrangement illustrated in Fig. 2, sending and receiving distributers 47 and 37, respectively, are illustrated. Associated with the sending distributer is a transmitter 39, comprising a plurality of selectively operable contacts 41, 42, 43, 44 and 45, and a common contact 46. These contacts may be selectively controlled by manually operable means or by automatic means, such as tape transmitters, both of which are well known in the art. Each of the transmitter contacts 41 to 45, inclusive, is connected to separate segments of the sending distributer, and they are adapted to be connected to the line circuit L through the sending distributer ring 48, whenever brushes 49 and 50 pass over the respective distributer segments. Associated with the distributer 37 is a receiving mechanism 51 comprising a plurality of electroresponsive devices which may be employed for the purpose of relaying the

received impulses or for operating a suitable recording instrument, for example, a printer. The distributer 37 and selecting mechanism 51 may be operated in response to signals transmitted from a distant station, or they may be employed as home recording instruments to provide a home copy of the characters transmitted from the distributor 47.

The distributer brush arms 17 and 18 are frictionally mounted on the constantly rotating shaft 16 and are normally restrained from movement by means of the stop-arms 34 controlled by the release magnets 32. In the particular embodiment herein illustrated the line circuit is shown closed.

Let it be assumed that the transmitter 39 is operated to transmit a character signal represented by two marking impulses followed by three spacing impulses, thereby closing contacts 41 and 42 without altering the normal position of contacts 43, 44 and 45. The closure of the common transmitter contact 46, which contact is closed whenever a character combination is set up, will establish an energizing circuit through the release magnet 32 from grounded battery 55, distributer ring 56, brushes 58 and 59, conductor 60, winding of magnet 32 and contact 46 to ground. The instant magnet 32 is energized, it withdraws the extension arm 34 from engagement with the distributer brush arm 18, thereby permitting the brush arm to rotate, due to its frictional engagement with the rotating shaft 16. The instant the brush arm 18 is released and the brush 50 passes off of segment 61, the line circuit L is opened and the line relay 62 permits its armature 63 to fall back and engage its back contact, thereby completing a circuit from ground to battery 64, distributer ring 65, brushes 66 and 67, segment 68, release magnet 32, contact and armature 63 and switch 69 to ground. The energization of the release magnet 32 at the receiving station operates to effect the release of the distributer brush arm 17 in the same manner as the distributer brush arm 18 above referred to.

The distributer brush arms at both the sending and receiving stations have now been released, and assuming that the speed of the driving motors has been adjusted so that the distributer brushes pass over corresponding segments at the sending and receiving stations in isochronism, it will be understood that selecting magnets 71 and 72 will be operated by reason of the closure of transmitter contacts 41 and 42, and that selecting magnets 73, 74 and 75 will remain unenergized because transmitter contacts 43, 44 and 45 have not been closed. The instant the distributer brushes pass off of the start segments or the segments included in the circuits of the release magnets 32, the magnets will be deenergized and the stop-

130

arms will move into position to engage the brush arms at the completion of each revolution. Thus for the transmission of each character combination, the distributers make 5 one revolution and stop until a new character combination is set up and the distributer brush arms are again released.

What is claimed is:

1. A current impulse distributing mechanism comprising a distributer face consisting of continuous and segmented rings, a rotary member, distributer brushes carried by said rotary member for interconnecting predetermined ones of said rings, a revolving shaft on which said member is frictionally mounted, driving means for said shaft, adjustable means carried by said revolving shaft for altering the speed of said driving means, and means for altering the adjustment of said adjustable means while the shaft is in motion.

2. A current impulse distributing mechanism comprising a distributer face composed of a plurality of continuous and segmented rings, means for orienting said distributer face, a rotary arm, brushes carried by said rotary arm and adapted to traverse said distributer rings, a revolving shaft on which said rotary arm is frictionally mounted, driving means for said shaft, centrifugally operable means carried by said revolving shaft for controlling the speed of said driving means, and means for adjust-

ing said centrifugally operable means while the shaft is in motion.

3. A distributing apparatus comprising a plurality of distributer faces, a housing supporting said faces, rotary brush arms, a plurality of brushes carried by each of said arms for traversing said distributer faces, mechanism mounted within said housing for rotating said distributer brush arms, means supported by said housing for releasing and arresting the distributer brush arms once per revolution, and means for guiding said releasing and arresting means to prevent vibration thereof.

4. A distributing mechanism comprising a plurality of distributer faces frictionally mounted in a supporting member, means for altering the phase relation of said distributer faces, a rotary brush arm for each of said faces, distributer brushes carried by each of said arms for traversing the respective distributer faces, a release magnet, means for energizing said release magnet to withdraw a stop member from the path of said distributer arm, means for returning the stop member to normal on the deenergization of said magnet, and a bifurcated member for supporting said stop member to prevent vibration thereof when engaged by said rotary distributer arm.

In witness whereof I hereunto subscribe my name this 20th day of March, A. D. 1919.

PAUL M. RAINY.
